C. E. CHAPMAN.

AUTOMATIC ADJUSTABLE SHELF TRAY.

FILED JULY 30, 1920.

Inventor
Charles E. Chapman
By Brown, Bettcher & Piemers
Attorneys.

UNITED STATES PATENT OFFICE.

CHARLES E. CHAPMAN, OF CHICAGO, ILLINOIS.

AUTOMATIC ADJUSTABLE SHELF TRAY.

Application filed July 30, 1920. Serial No. 400,165.

To all whom it may concern:

Be it known that I, CHARLES E. CHAPMAN, a citizen of the United States, residing at Chicago, in the county of Cook and State 5 of Illinois, have invented a certain new and useful Improvement in Automatic Adjustable Shelf Trays, of which the following is a full, clear, concise, and exact description, reference being had to the accompanying 10 drawings, forming a part of this specification.

My invention relates to jewelry trays and more particularly to that type of tray wherein carded jewelry is adapted to be carried 15 for display in show cases and windows.

While my invention relates to trays for carrying carded jewelry and the like, I do not intend to limit myself to such use solely, as it is apparent that by slight variations 20 in structure, the tray may be used for displaying objects of similar or even of dissimilar character.

Generally it has been customary, heretofore, in the practice of the jeweler, to remove the jewelry on display either in the 25 show cases or in the windows to the vault at the end of the day. This causes an unlimited amount of labor, especially if the stock on hand is large. The jewelry re- 30 moved to the vault has to be arranged with unusual skill, as the size of the latter is generally limited. Furthermore, jewelry is of such a character as to warrant only careful handling. In order to best display the jewelry in the tray, it is customary to provide 35 grooves in the latter to receive and permit the jewelry to protrude therefrom a considerable distance, so as to have it prominently stand out. This protrusion of the jewelry 40 prevents the same from being placed in the vault while in the tray, as damage to the jewelry is apt to occur by stacking of the trays above one another. This can only be overcome by removing the jewelry from the 45 tray, and hence it is apparent that additional labor is caused.

It is, therefore, the primary object of this invention to overcome the above difficulty by providing a tray which suitably retains 50 the jewelry during the period of display, permitting it to protrude a suitable distance in order to secure the desired prominence, and which may be stacked away in the vault with the jewelry disposed therein in such

a manner as to eliminate any damage to the 55 jewelry.

As a further object, provision has been made whereby adjustment may be readily made in order to dispose the jewelry in the tray in a proper position to permit close 60 stacking of the trays. The adjustment is automatic, and therefore, has for its purpose the saving of time and labor.

A further object of this invention resides in the arrangement of a shelf within the 65 tray whereby the jewelry may be positioned at any angle while displaying in order to secure the proper angle of light reflections, without necessarily controlling the position of the tray. Thus the trays may be positioned closely together in the showcase or window, the automatic adjustment of the shelves taking care of the light reflections on the jewelry.

Other advantages of my invention not 75 hereinbefore set forth will appear from the following detailed description and claims taken with an inspection of the accompanying drawings wherein I have illustrated various ways in which my invention may be 80 embodied. The particular tray shown is merely illustrative and the details thereof may be varied.

Figure 1 is a top plan view of a jewelry tray embodying the preferred mode of my 85 invention, and illustrating the shelves in closed position;

Figure 2 is a detailed fragmentary view taken on line 2—2 of Figure 1;

Figure 3 is a detailed fragmentary view, 90 illustrating the opposite side of the view shown in Figure 2;

Figure 4 is a view of a stack of trays to illustrate the manner of stacking the trays within the vault;

Figure 5 is a side elevational view of a tray in which is embodied a modified form 95 of my invention;

Figure 6 is a similar side elevational view;

Figure 7 is an isolated perspective view 100 of the shelves having in connection therewith the modified means of actuating the same; and

Figure 8 is a detailed fragmentary view taken on line 8—8 of Figure 5.

Referring to Figure 1, the tray 1, in which my invention is embodied, comprises the side walls 2 having the ledges 3. The

ledge 3 is preferably disposed along the lower end of the wall 2 and provides an open bottom for the tray, the purpose of which will hereinafter be mentioned. Before or after the assembly of the tray, holes are bored in the inner opposite faces of one pair of sides. These holes preferably face each other and are in parallel alignment.

When the tray is assembled and the sides 10 are properly secured together, the sides, in which the holes are provided, are expanded slightly to permit the insertion of the rods 4. The rods 4 carry shelves 5 which may be made out of any kind of material desired, 15 although sheet metal better serves the purpose. The form of shelf shown herein is merely exemplary, illustrating one of the various ways of suitably retaining a card 9 to which is fastened some articles for sale, 20 such as jewelry. The shelf 5 may be made from one piece of metal, the stamping of which is performed in one operation. The lower portion 7 during the stamping operation, is provided with the spring retaining 25 fingers 8 which serve to bear against the card 9 to hold the same in proper position while in the tray. These fingers are so formed that they resiliently bear against the back 10 of the shelf 5, and flare outwardly at the upper end. Preferably, the 30 fingers 8 are provided in pairs for each card 9 which have a wedged engagement with the same and the back portion 10. That portion between the respective fingers of each 35 pair is preferably retained as shown at 11, so as to present a finished effect. The portion 10 may be covered with any kind of fabricated material desired. It is to be here noted that the entire lower portion 7 of the 40 shelf 5 may be formed in one piece if so desired. At one end of the shelf 5 a lug 12 is provided which is at right angles to the back 10. To the lug 12 is riveted the tension member 13 by means of the rivets 14.

Referring to the detailed views of Figures 45 2 and 3, the tension member 13 terminates at the rear end in such a manner that a detent 15 projects from the upper edge preferably at right angles to the sides thereof. 50 Lying adjacent to the tension member 13 at this end is the spring toothed latch member 16 which is carried by the ledge 3 in any suitable manner. The side adjoining this 55 part of the tray is provided with the slot 17 for the reception of the finger 18 formed integral with the spring latch 16.

The detent 15 is adapted to engage the teeth of the latch member 16 upon adjustment of the shelves 5 within the tray 1. 60 When it is desired to release the shelves 5, the finger 18 is manually actuated in the slot 17 which moves the latch member 16 outwardly, so that the detent 15 is free to disengage the teeth and drop downwardly by 65 gravity, the shelves also dropping therewith

to lower position in the tray. The finger 18 preferably does not project beyond the slot 17 but lies flush with the outside face of the tray. This permits easy and close stacking of the trays within the vault at the end of 70 the day. Close stacking of the trays is highly desirable as vaults are usually of limited capacity.

In Figures 5 to 8 wherein I have shown a modified form of adjusting means for the shelves 5, the tension member 20 at the rear end frictionally engages a bar 21 which is rigidly fixed to the side 2. Adjacent this end of the tension member 20, a rivet 22 is carried which is threaded at the free end for 80 receiving the thumb bolt 23. The thumb bolt 23, in a manner similar to the finger 18 is disposed in the slot 24 which is in this case arcuate. Movement of the thumb bolt 23 in this slot raises and lowers the shelves 85 5, the position of the shelves 5 being retained by the frictional engagement of the tension member 20 with the bar or plate 21. Threading of the thumb bolt 23 upon the rivet 22 adjusts the tension of the member 90 20, this tension controlling the degree of engagement of the member 20 with plate 21.

As is well known to one skilled in the art of decorating show cases or windows, it is necessary at times to dispose the articles of 95 display about, so that a perfect symmetry of composition may be had. This often requires, for instance in the jewelry industry, that the trays stand vertical, semi-vertical, or possibly lie horizontal. Hence, if the 100 means within the tray, which carries the jewelry were not adjustable, a proper reflection of light could not be obtained, which is very necessary in order to have jewelry 105 on display attractive. If the factor of light reflection is more important, a large amount of space is wasted.

As is shown in Figures 6 and 7 this disadvantage is totally eliminated by my invention, as the shelves 5 may be properly 110 adjusted to meet the prevailing needs. In Figure 5 the tray is semi-vertical, yet the carded jewelry of the rear tray is sufficiently visible and in position to permit full light reflection. In Figure 6 the tray is almost vertical. According to the arrangement shown 115 the tray 1 is constructed with an open bottom as before described, which allows the light to clearly pass therethrough, thereby greatly adding to the volume of light admitted.

It is to be here noted that the important features of this invention may be embodied in various ways in other devices.

It is apparent that automatically adjusting the shelves 5 so that it is not necessary to remove the jewelry from the tray at the end of the day, but permits it to be stored in the vault in the tray, and that the feature of acquiring a proper light reflection on the 120 130

jewelry in the tray while on display in the window or showcase without necessarily limiting the position of the tray may be had by arrangement other than shown, and consequently I do not intend to be limited to the showing made.

I claim:

1. In a device of the class described, the combination with a display tray, of a plurality of shelves pivotally mounted in said tray, said shelves being provided with means for retaining articles of display, a movable member lying adjacent and pivoted to said shelves, a releasable latch member disposed at one end of said movable member, said releasable latch member adapted to engage said movable member only when to automatically lock said shelves in adjusted position.
2. In combination, a tray comprising, a rectangular frame, shelves substantially of a greater height than the frame pivoted therein, a common element pivotally connecting said shelves and lying parallel to the side plane of the tray, a latch member for engaging one end of said common element

whereby the shelves may be held in any angular position, said latch member having teeth thereon and being arranged in the frame so that the same may tensionally engage the common element.

3. A jewelry tray comprising, a rectangular frame, shelves pivoted in said frame and adapted to carry carded jewelry and the like, said shelves comprising a back portion embracing a pivot shaft at the lower end and flaring outwardly a distance therefrom to provide a wedging socket in which the jewelry cards may be carried.

4. In combination, a rectangular tray member having vertical side and end walls, shelves pivoted at their ends directly in the side walls of the tray and being adapted to fold within the tray, a lock member, a common connecting member co-operating with said lock member for locking the shelves positively in a desired position, said lock member being accessible through a wall of the tray.

In witness whereof I hereunto subscribe my name this 27th day of July, 1920.

CHARLES E. CHAPMAN.
